UNITED STATES PATENT OFFICE

JOHN C. PAGE, OF BRAWLEY, CALIFORNIA.

WHEELBARROW.

1,157,034.

Specification of Letters Patent.

Patented Oct. 19, 1915.

Application filed September 29, 1914. Serial No. 864,135.

To all whom it may concern:

Be it known that I, JOHN C. PAGE, a citizen of the United States, residing at Brawley, in the county of Imperial and State of California, have invented new and useful Improvements in Wheelbarrows, of which the following is a specification.

This invention is an improved wheel barrow, especially adapted for use for carrying building materials, earth and other like material, the invention consisting in the construction, combination and arrangement of devices hereinafter described and claimed.

One object of the invention is to effect improvements in the construction of the frame.

Another object of the invention is to effect improvements in the construction of the legs.

Another object is to effect improvements in the construction of the braces.

In the accompanying drawings:—Figure 1 is a side elevation of a wheel barrow constructed in accordance with my invention.

Fig. 2 is a rear elevation of the same. Fig. 3 is an inverted plan of the same. Fig. 4 is a vertical transverse sectional view on the plan indicated by the line *a—a* of Fig. 1.

The body of the wheel barrow is made of sheet metal and has upturned inclined sides and ends so that it can be dumped from the front or from either side. The bottom is flat. The entire body may be made of a single piece.

The handles 1 are formed integrally with the sides 2 of the frame, said sides and handles being formed from a V-shaped tube which may in practice be a suitable length of iron or gas pipe. The handles are upturned as shown and the sides 2 of the frame 40 are formed with downwardly and forwardly inclined offset portions 3.

The wheel 4 is arranged in the bight or apex of the frame, between the forwardly converging portions of the sides 2 and its axle 5 is mounted in bearings 6 in semi-tubular blocks 7 which are arranged on the under sides of the forwardly projecting portions of the frame.

A cross bar 8 which in practice is a flat metallic strip or bar, connects the rear portions of the side members 2 of the frame and

is formed with integral eyes 9 through which said side members extend. On the under side of this cross bar are a pair of standards 10 each of which is substantially U-shaped, and is bent from a single strip or bar of metal. Each leg has oppositely extending lugs 11 at its upper end. The outer lugs of the legs are arranged in the open sides of the eyes 9 of the cross bar 8 and at the inner sides of the members 2, the inner lugs of the legs being arranged in overlapping relation, one upon the other. Bolts 12 are passed through the overlapping portions of the eyes, the lugs and up through the bar 65 and through the bottom of the sheet or plate metal body 14, so that said bolts not only secure the legs to the cross bar but also secure the eyes around the side members 2 and 70 secure the body of the wheel barrow on said cross bar. A front cross bar 15 which is also made of a strip or flat bar of metal, is arranged at a suitable distance in advance of the bar 8, bears under the bottom of the body and is formed with eyes 16 which embrace 75 the side members 2. Braces 17 have their upper ends secured in the open sides of said eyes and their rear ends secured in the lower ends of the legs, bolts 18 being employed to 80 secure the braces to the legs and bolts 19 being employed to secure the braces to the cross bar 15 to also secure the eyes 16 and to secure the body of the wheel barrow on the said cross bar 15.

Front braces 21 have their upper ends 85 bolted to the front side of the body as at 22 and have their lower ends secured on the forwardly extending portions of the frame members 2 by bolts 23, said bolts also securing the blocks 7 in place.

It will be observed and understood that my improved wheel barrow is entirely constructed of metal, is extremely strong and durable, and may be readily manufactured at slight cost.

Having thus described my invention, I claim:—

In a wheel barrow a V-shaped tubular frame having its rear ends upturned and bent to form handles, cross bars connecting the side members of said frame and having eyes engaging said side members, a body

bearing on said cross bars, legs under the rear cross bar, braces connecting the lower ends of the legs to the front cross bar, bolts securing said braces and also securing the 5 front cross bar to the body and bolts securing the legs to the rear cross bar and also securing the latter to the body.

In testimony whereof I affix my signature in presence of two witnesses.

JOHN C. PAGE.
